GRAVEL SEPARATOR AND SCRUBBER

Ellis Johnson, Long Branch, N. J.

Application May 16, 1955, Serial No. 508,713

9 Claims. (Cl. 209—270)

This invention relates to a gravel separating device and more particularly to a pair of rotating drums into which the gravel, clay and sand mixture are conveyed with a water jet. The mixture is thoroughly agitated to disintegrate and separate the mixture and in which the mixture will be worked back from the gravity end of each rotating drum to be screened and separated.

In the normal procedure of screening or separating gravel from the ingredients with which it is found in a natural state, the mixture is loaded into either a rotating drum that is tilted to allow the mixture to feed towards the gravity end of said drum while being vibrated or stirred during the rotation of the drum. This method will tend to break up the clay from the solids and assist in washing out the clay from the solids, the mixture being discharged from the gravity end of the rotating drum. However this method, unless carried over a great length, will not provide a clean separated and graded gravel.

It is an object of this invention to provide a continuously operated apparatus which will thoroughly clean the natural clay, sand, gravel formation and screen and separate the elements into a clean properly graded sand and gravel.

A further object of this invention is to provide a continuously operated apparatus in which the sand, clay, gravel mixture is jetted into the apparatus with a stream of water and in which the water mixture is received in a rotating drum with a plurality of blades to thoroughly break up the mixture and in which the drum is tilted so that the clay will be washed out of the higher portion of the drum with the action or flow of the water and in which the heavier particles will back up within the drum to be discharged into a second drum for a similar operation.

A still further object of this invention is to provide a gravel, clay, sand mixture separating apparatus that is continuously operated and in which a pair of rotating drums are provided in which the first drum is tilted with the lower end closed to receive the sand, gravel, clay mixture and the upper end open and provided with a screening device and in which the second drum is similarly tilted with the lower end closed to receive the gravel mixture and the upper end open and provided with grading screens to properly grade the gravel as it leaves the second rotating drum.

Other objects of this invention shall be apparent by reference to the accompanying detailed description and the drawings in which

Fig. 1 is an elevational view of the apparatus partly in cross section,

Fig. 2 is a cross sectional view taken on line 2—2 of Fig. 1,

Fig. 3 is a cross sectional view taken on line 3—3 of Fig. 1,

Fig. 4 is a perspective view illustrating one portion of the apparatus, and

Fig. 5 is a schematic view of a further embodiment of this invention.

2

Referring to Fig. 1 there is illustrated a gravel washing, scrubbing and sieving apparatus which includes a pair of rotatable drums 10 and 11 that are positioned adjacent to each other. Drum 10 includes a drive shaft 12 which is affixed to the center of the closed end wall 14 of drum 10. Drum 10 at its opposite end is provided with a cylinder screen 15 attached to the end 16 of drum 10 with the opposite end open. Screen 15 is approximately a $\frac{3}{16}$ " mesh. Drum 10 is mounted to rest upon a pair of rollers 18 positioned in spaced relationship to support drum 10 yet permit drum 10 to rotate on the rollers, the third support for drum 10 being the drive shaft 12, drive shaft 12 being supported in a bearing 19, the bearing in turn being mounted in a standard 20. The rollers 18 are also rotatably supported in standards 21. Drive shaft 12 is provided with a gear 22 affixed to shaft 12, the gear 22 meshing with a small pinion gear 23, pinion gear 23 being carried by a shaft 24, shaft 24 in turn being carried by a pair of pivotally supported arms 25 and 26, the arms 25 and 26 being pivoted on the drive shaft 12. The pinion gear 23 is keyed to shaft 24 and shaft 24 is provided with a drive pulley 28. Thus it is apparent that a belt drive may be provided to the pulley 28 which will in turn transmit the drive force by means of shaft 24 and pinion 23 to the drive gear 22 and in turn drive shaft 12 to rotate drum 10. The preferred rotative speed is approximately 12 R. P. M. Drum 10 on its internal surface is provided with a plurality of blades. The end wall 14 as illustrated in Fig. 2 illustrates the plurality of blades used to pick up and stir the contents of the drum. Fig. 1 also illustrates an elongation of some of the blades for the full length of the drum to insure a thorough stirring or agitating action and to assist in picking up the gravel and mixture from the bottom of the drum during its rotation.

The second drum 11 is similar in construction to the first drum, that is, it is provided with a similar end wall 14A and drive shaft 12A and exactly the same type of drive mechanism. Drum 11 is similarly supported on a pair of rollers 18A. Drum 11 is similarly provided with a rotary screen 15A at one end thereof. However screen 15A is divided into three different size mesh sections, that is, the first mesh area adjacent to the drum is a $\frac{1}{4}$ " grit screen, the second portion of the screen is a $\frac{3}{8}$ " mesh and the outer area of the screen is a $\frac{5}{8}$ " mesh. Any gravel of a larger size than $\frac{5}{8}$ " will be dumped out of the open end and is considered overflow. It is to be noted that both drums 10 and 11 are mounted in a tilted relation, that is, with the closed end of the drum lower than the open or screened end of the drum. It is also to be noted that the open $\frac{3}{16}$ " mesh screen end of drum 10 is positioned adjacent to the open screened end of drum 11. A material carrying chute 30 is provided of such a length that it extends from within drum 10 adjacent to the closed end to a position above drum 11, the enlarged open end of chute 30 being in a position where it may be easily loaded such as by a conveyor belt 31. The conveyor belt is not a part of this invention. The conveyor belt is a standard type of loading device for material. The chute 30 at its open or mouth end is provided with a water nozzle 32. The nozzle is directed down into the chute 30 so that when gravel, sand and clay as a mixture is dumped into the mouth of chute 30, a stream of water from spout 32 will assist in washing the material downward through the chute into the drum 10 where the mixture will be thoroughly agitated and the rotation of the drum will break up this material assisting the water in dissolving the clay from the mixture. The water and clay mixture will overflow from the open end of the drum while the sand and gravel continues to build up within drum 10. As drum 10 becomes filled with the mixture, it will back up toward the open end of the drum and

the washed aggregate will fall into the screen area. The finer particles such as sand will be sieved out of this mixture passing through the screen. For convenience a box 34 may be provided under the screen area. The water and clay solution will fall into this box as well as the sand. The sand will settle to the bottom and the water, clay mixture will continuously wash off. At the open end of the screen 15 there is provided the mouth or enlarged end 35, Figs. 1 and 3, of a chute 36, chute 36 extending downward into drum 11 adjacent to the closed end of the drum. Thus the gravel mixture that backs up in drum 10 and passes through the small screen area of drum 10 will be dumped into chute 36. A water jet or spout 37 is provided at the upper or mouth end 35 of chute 36 to assist in washing the gravel mixture down through chute 36 into drum 11, the gravel entering drum 11 will be thoroughly scrubbed in drum 11 due to the rotation of drum 11 at an approximate speed of 12 R. P. M. and the action of the water. The blades within drum 11 will continuously lift and agitate the mixture therein picking up the heavier particles lifting them and in turn dropping them on the mixture until the mixture or gravel therein builds up sufficiently to back up in drum 11 away from the closed end and overflow into the screen area. The smaller particles of gravel that will pass through a $\frac{1}{4}$ " screen will be deposited as illustrated in Fig. 4 into the first hopper 40. The larger particles of gravel that will pass through a $\frac{3}{8}$ " screen will be deposited into the second hopper 41 and the larger particles of gravel that will pass through a $\frac{5}{8}$ " screen will be deposited into the last hopper 42. Any particle of gravel greater than $\frac{5}{8}$ " is considered overflow and will in turn be dumped out the open end of the last screen. Drum 10 and drum 11 are both provided with drip rings 43 and 44. It is apparent that the drip ring 43 is mounted at the open end of drum 10 to prevent the water overflowing from drum 10 from running down towards the lower end of drum 10. This would carry the clay and water back on the bearings 18, whereas it is intended to dump the clay and water into box 34. Likewise the drip ring 44 is positioned at the open end of drum 11 on its exterior for a similar purpose. In operation, gravel, sand and clay are loaded by means of a conveyor belt into chute 30 and jettied through chute 30 into drum 10 where the mixture is not only washed to dissolve the clay but the larger particles being lifted and dropped tend to break up the clumps of clay found in the mixture. The mixture will, because of its agitation by drum 10, be thoroughly broken down to a fairly clean aggregate and as the mixture passes through screen 15 it will have all of the sand removed therefrom. The gravel leaving screen 15 and entering chute 36 will be jettied down chute 36 into drum 11 and will be thoroughly scrubbed in drum 11. The resulting clean aggregate will in turn be screened through the appropriate sized screens at the open end of drum 11 thus sorting or classifying the gravel into three groups according to size.

Referring to Fig. 5 it is apparent that either drum 10 or drum 11 may be positioned in a perfectly level position and still effectively clean the gravel mixture. In fact the level position would probably increase the output of the device. However the tilted position illustrated in Fig. 1 is provided to insure a clean mix from the first charge of gravel making it impossible to dump any gravel that has not been thoroughly scrubbed.

Although exact size of the drum 10 and drum 11 is not important, it is apparent that the device may be made quite large to handle a large quantity of material. Although the screened ends of the drums are illustrated to define the invention, the size or length of the screened areas may be varied according to the mixture being handled, that is, with a mixture having considerable sand and clay in same it may be necessary to provide a fairly large $\frac{3}{16}$ " mesh screen area to insure a thorough screen-

ing of all sand from the mixture. Whereas with a cleaner mixture a small area may be sufficient. Likewise with the screened areas of drum 11, if the aggregate is a fairly even mix, the three areas may be in similar proportions. Whereas if the aggregate runs towards the heavier or larger size, the smaller screens may be reduced in length. However the screened area may be varied to accommodate the particular needs in use. Although one type of drive is illustrated for each drum, it is apparent that motors may be mounted at the end of each drum or any other type of drive to produce a fairly slow R. P. M. drive. Although the drums are illustrated as being supported by a three point suspension they may be similarly mounted on four or more point suspension without departing from the spirit of this invention. Although the drums are illustrated as being loaded by a pair of chutes they may be similarly loaded with conveyor belts without departing from the spirit of this invention as long as the drums are loaded with the mixture and a water jet to produce the necessary scrubbing and dissolving of the clay and foreign matter from the gravel. Various changes may be made in the configuration of the blades or stirring surfaces without departing from the spirit of this invention and this invention shall be limited only by the appended claims.

What is claimed is:

1. An apparatus for separating gravel from its natural clay and sand formation which includes an inclined feeding chute with a water jet at the upper end of said chute to assist in washing and pushing said gravel formation through the chute, a rotatable drum into which the chute extends, said rotatable drum being closed at one end and provided with a separating screen at the opposite end, said drum supported on rollers and said drum provided with means to rotate said drum, the closed end and inner periphery of said drum provided with a plurality of blades, said chute extending to a point adjacent to the lower portion of said drum and adjacent to the closed end.
2. In a device according to claim 1 in which the drum is inclined with the closed end of said drum lower than the open end of said drum.
3. In a device according to claim 1 in which a drip ring is affixed to the outer periphery of the drum adjacent to the open end of said drum to which the separating screen is attached.
4. An apparatus for separating gravel from its natural clay and sand formation and thoroughly scrubbing said gravel which includes an inclined feeding chute with a water jet at the upper end of said chute to assist in washing and pushing said gravel formation through the chute, a pair of rotatable drums, said rotatable drums being closed at one end and provided with a separating screen at the opposite end, said drum supported on rollers and each drum provided with means to rotate said drum, the closed end and inner periphery of each drum provided with a plurality of blades, said chute extending to a point adjacent to the lower portion of said first drum and adjacent to the closed end, a second chute inclined into said second drum and positioned with its open or mouth end adjacent to the open end of said first drum, said second chute extending into said second drum to a point adjacent to the lower portion of said drum and adjacent to the closed end, said second chute provided with a water jet at the upper end of said chute to assist in washing said gravel formation through the chute, said first drum is positioned slightly higher than said second drum so that the overflow of gravel from said first drum will fall into said second inclined chute to carry said gravel into said second drum.
5. In a device according to claim 4 in which the first drum is inclined with the closed end of said drum lower than the open end of said drum.
6. In a device according to claim 4 in which the first drum is inclined with the closed end of said drum lower than the open end of said drum and in which said second

drum is also inclined in an opposite direction with the closed end of said drum lower than the open end of said drum.

7. In a device according to claim 4 in which a drip ring is affixed to the outer periphery of said first drum adjacent to the open end of said drum to which the separating screen is attached and in which a second drip ring is affixed to the outer periphery of said second drum adjacent to the open end of said drum to which the separating screen is attached.

8. An apparatus for separating gravel from its natural clay and sand formation and thoroughly scrubbing said gravel which includes an inclined feeding chute with a water jet at the upper end of said chute to assist in washing said gravel formation through the chute, a rotating drum, said drum being closed at one end and provided with a separating screen at the opposite end, said drum supported on rollers and provided with means to rotate said drum, the closed end and inner periphery of said drum provided with a plurality of blades, said chute ex-

10

15

20

tending to a point adjacent to the lower portion of said drum and adjacent to the closed end and in which the separating screen affixed to said drum is divided into a plurality of different screens.

9. In a device according to claim 8 in which the drum is inclined with the closed end of said drum lower than the open end of said drum.
